UNITED STATES PATENT OFFICE

CHESTER D. AINSWORTH, OF WOLLASTON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

HIGH CURRENT ELECTRIC SWITCH

Application filed May 31, 1930. Serial No. 458,876.

This invention relates to electric switches and particularly to switches which employ, in addition to the main current carrying contact members, auxiliary contact members between which the circuit interrupting arc is drawn. The usual down break electric switch consists of a pair of upstanding conducting studs terminating at their lower ends in fixed contact members which are adapted to be electrically connected by a horizontal bridging member which is vertically movable into and out of contact engaging position. The magnetic flux in the vicinity of the U-shaped current path thus formed reacts on the movable bridging member to move the contact members thereof, and particularly the resiliently mounted arcing contact members, downwardly out of engagement with their cooperating fixed contact members, thus to break the circuit and cause arcing and burning at the contacts.

It is an object of this invention to provide a current conducting loop in the vicinity of and including a movably supported contact member which is so arranged that the magnetic forces set up by the current flowing in the various parts of the loop react on the contact member and urge it in a switch closing direction into pressure engagement with its cooperating fixed contact member.

It is a further object of the invention to provide a movable switch member having a relatively long, generally horizontal contact member which is pivotally supported at one end, and a supporting structure therefor including a conducting member which is disposed in the same vertical plane and is generally parallel with said contact member, and through which the current traversing said contact member is arranged to pass in a direction to react magnetically on and urge said movable contact member in a switch closing direction.

A further object of the invention is the provision of a movable switch member having two superposed generally horizontal conducting members one of which members comprises a movable contact member which is pivotally supported at one end, whereby the magnetic field set up by the current travers-

ing the switch reacts on the movable contact member throughout its length and at points remote from its pivotal support in a direction to urge said contact member upwardly in a switch closing direction.

A yet further object is to provide a movable switch member having a generally vertically disposed U-shaped current path therethrough, one arm of the U-shaped path comprising a relatively long contact supporting arm having a pivotal support at one end and a contact member at its free end.

A still further object is the provision of a movable switch member having a movable contact member comprising a relatively long and horizontal arm which is pivotally supported at one side of said switch member and extends across and is provided with an arcing tip at the other side of said switch member, and conducting means disposed beneath said arm and in series therewith whereby to set up a magnetic field in the vicinity of said arm when a heavy current traverses the switch circuit which reacts on said arm throughout its length in a switch closing direction.

A further object of the invention is the provision of a movable switch member including a central vertical insulating rod and a movable contact arm which is pivotally supported at one side of said rod and extends in a generally horizontal direction across and terminates at the other side of said rod in a contact tip, and a rigid conducting support for said arm which constitutes a current conducting path which is parallel with and reacts on said arm substantially throughout its length to urge it in a switch closing direction.

In accordance with this invention, the contact or arcing members are carried at the ends of long arms which are pivotally supported on opposite sides of the lifting rod. An object of the present invention is to provide conductors which will connect the pivoted end of said arms and at the same time be so arranged that they will react on the arms in the proper direction to urge the arcing members upward.

A further object is generally to improve the construction and performance of electric switches and contact structures therefor.

Fig. 1 is a side elevation of the contact structure embodying the present invention.

Fig. 2 is a sectional view taken along line 2—2 of Fig. 1.

Fig. 3 is a section along line 3—3 of Fig. 2.

Fig. 4 is a plan view of a clamping member.

Fig. 5 is a side elevation of the clamping member of Fig. 4.

Fig. 6 is a plan view of a connector.

Fig. 7 is a diagrammatic perspective diagram of the current path through the movable switch member.

Fig. 8 is a sectional detail taken along line 8—8 of Fig. 2.

The switch herein shown includes a pair of vertical conducting rods, or studs, 10 which are supported in insulating bushings 12. Contact supporting blocks 14 are fixed to the lower ends of said studs and are provided with lower horizontal seats 16 on which the stationary contact members are detachably supported. Said stationary contact members comprise laminated brush members of the non-reactive or inverted type of which one or more is adapted to be carried at the lower end of each stud. The shank portions 18 of said brush members are enclosed by sheaths 20 and attaching bolts 22 are extended through the sheath and the shank portion of the brush and are screw-threaded into said blocks 14. Said brushes also include the downwardly and inwardly directed toe portions 24 which terminate in the generally horizontal contact faces 26. In the switch here shown three parallel brushes are associated with each conducting stud although the number of brushes may vary in accordance with the current capacity of the switch. Stationary contact or arcing members comprising horizontally disposed cylinders or rolls 28 are carried by each of said studs beneath the intermediate brush member thereof. Said arcing members are supported between the depending spaced arms of a U-shaped frame 30 which is fixed beneath the middle brush member by the attaching bolts 22 of the brush member.

The movable switch member includes a vertical insulating switch rod, or lifting rod, 32 and a transverse main current carrying bridging member 34 which is provided with upper plane contact faces 36 which are adapted to cooperate with the horizontal contact faces 26 of the several brush members in the usual manner. The bridging member 34 is supported loosely at the lower end of the lifting rod 32 whereby to permit a degree of pivotal movement thereof about its supporting rod. Said lifting rod is provided with an annular shoulder 38 which defines the upper limit of a downwardly and outwardly flared end portion which is adapted to carry the supporting means for the main bridging member and also the auxiliary movable arcing members hereinafter to be described.

Said supporting means comprises a pair of

similar clamping members 39 and 40, Fig. 2, one of which is shown most clearly in Figs. 4 and 5. Said clamping members are identical and each has a vertical tapered recess 41 which recess cooperates to provide a tapered passage that conforms with the flared or conical end portion 37 of the rod. Said clamping members are disposed on opposite sides of the switch rod and are held fixedly in place on said conical end portion by means of a pair of clamping bolts 42 one of which is disposed on either side of the switch rod and which are insulated from the clamping members by means of insulating bushings and washers 44 and 46. Said clamping members when in position on said rod are adapted to be spaced apart at their inner confronting faces whereby to provide a gap 48 therebetween. It will thus be evident that the two complementary clamping members are insulated from each other by the rod 32. Each of said clamping members is provided with an outstanding bracket 50 which terminates in an upstanding arm 52, which arms are disposed in a vertical plane including the insulating switch rod 32, and are received loosely between pairs of parallel depending flanges 54 of said bridging member, see especially Fig. 8. Pivot pins 55 extend transversely through said flanges 54 and the ends of said arms 52 whereby to support the bridging member for pivotal movement about said pins as an axis. Means are provided to insulate said bridging member and the pivot pins 55 from the upstanding arms 52 of the clamping members. To this end a cylindrical insulating bushing 56 surrounds each of the pins 55 in the flanges 54 and insulating washers 57 are carried by said bushing and interposed between the opposite faces of said arms 52 and the depending flanges 54 of the bridging member. The above arrangement prevents the conducting bridging member from establishing electrical connection between the insulated clamping members by which it is supported. The bridging member is provided with pairs of spaced vertical ribs 58 at opposite edges which are disposed on opposite sides of the pivot pins 55 which project somewhat beyond said bridging member. Cotter pins 60 extend through said ribs and said pins 55 and the insulating bushings 56 therefor, thus to prevent axial displacement of the pins and the bushings.

Each of said clamping members has a horizontal outstanding bracket 62 which is provided with an angularly related section 64. As shown most clearly in Fig. 2 when the clamping members are secured in position on the switch rod 32 the sections 64 of said arms are extended in opposite directions and terminate in upstanding bracket 66 which are disposed in line with the switch rod 32, but occupy diagonally opposite positions relative to the bridging member 34. Said outstanding

ing arms 62 are of good conducting material such as bronze or low resistance composition and are provided with integral depending ribs 68 thus to provide increased rigidity and strength. Said brackets 66 are provided with upstanding bosses 70 which engage the U-shaped insulating members 72 which are secured to peripheral depending ribs 74 on the bottom face of the bridging member 34. 10 When the bridging member is in a horizontal position, the insulating members 72 are adapted to be somewhat above the bosses 70 thus to permit a limited pivotal movement of the bridging member about the pivotal 15 supporting pins 54.

Each of said brackets 66 constitutes the support for a relatively long and generally horizontal contact supporting arm 76. Said arms are similar and are provided at one end 20 with spaced parallel bifurcations 78 which receive closely therebetween the upper end of a separate supporting bracket 66. A pivot pin 80 extends through said bracket and through and beyond said bifurcations and is held in 25 position by means of cotter pins at either end thereof. Said arms 76 are inwardly reflexed at a point intermediate their ends whereby to provide sections 82 adjacent their free ends which overlie and are parallel with the clamp- 30 ing members and particularly the sections 63 of said clamping members. Said arms 76 are provided with vertical seats 84 at their free ends and arcing members comprising horizontal cylinders or rolls 86 are secured fix- 35 edly thereto by bolts 88. Said arcing members, by reason of the bends in said arms 76 are centrally located in a common vertical plane with the switch operating rod 32.

Each of said clamping members is formed 40 with a vertical slot therein at the side opposite the extended bracket 62 to provide a seat 45 for the lower end of upstanding conducting bars 92 and 93 associated with clamping members 39 and 40, respectively, which are 50 secured fixedly thereto in good conducting relation by bolts 94. The bars 92 and 93 of said clamping members are electrically connected at their upper ends by means of a generally circular connector 96, Fig. 6, which 55 is provided with a central passage 98 there- through in which the switch rod 32 is freely located. Said connector has bosses 100 which are formed with vertical seats 102 to receive the upper ends of said bars 92 and 93. Bolts 60 104 serve to connect the upper ends of said bars mechanically and electrically to the connector.

Each of said contact supporting arms 76 is electrically connected with its supporting bracket 66 by means of a flexible conducting braid 106 which is electrically connected at its opposite ends to said contact member and bracket by means of attaching screws 108 and 109. Said arms 76 are adapted normally to 65 be biased for movement in an upward direc-

tion about their pivotal supports whereby to urge the movable arcing members 86 into engagement with the cooperating fixed arcing members 28. To this end a compression spring is provided on the extended ends of 70 each pivot pin 80 and has an intermediate depending portion 110 which bears against the inner vertical face of said brackets 66 and angularly related end portions 112 which are disposed beneath said arms 76 and exert a 75 pressure upwardly thereagainst in a switch closing direction.

Means are provided to limit the movement of the contact members 76 in their upward movement. Said means includes the vertical 80 upstanding rigid stop members 114 which are secured by bolts 116 to the inner faces of said sections 63 adjacent the clamping members. Said stop members are insulated from their supporting clamping members by suitable 85 means as the sheet insulation 118 and insulating washers 120 which are disposed beneath and around the attaching bolts 116. At their upper ends said stop members are provided with angularly related ears 122 90 which overlie said arms 76 and against which said arms are adapted to abut in the switch open position thereof. The stop members 114 also constitute vertical abutments against 95 which the inner faces of said contact supporting arms rest and which resist the magnetic forces tending to attract the parallel arms due to the currents flowing therein.

In Fig. 7 the current path through the movable switch member has been diagrammatically illustrated. Assume at a given instant that the current is passing through the switch from the left hand to the right hand arcing member 86 as indicated by the arrows 100 in Fig. 7. It will be obvious that current flowing in each contact arm 76 and that flowing in the current path of the clamping member therebeneath is in opposite directions. Due to the close relation of these parallel current conducting paths a strong magnetic 105 reaction is set up which tends to repel the contact arms 76 in an upward direction. From an inspection of Fig. 2 it will be evident that by the disposition of the conducting bars 92 110 and 93 of the clamping member closely adjacent the bracket 66 of the opposite clamping member that the current flowing through the clamping members must traverse a path parallel with the contact arms 76 which extends substantially along the entire length thereof. 115

Due to the length of the pivoted contact arm 76, the reaction of the current flowing in the section 63 of the clamping member, which is directly beneath the contact member and is disposed at a considerable distance from its pivot pin, results in a relatively strong force. By the arrangement of the long contact arms 76 which are pivoted on opposite sides of the switch member from which their arcing members are located, it is possible to obtain suffi- 120 125 130

cient reaction due to the localized magnetic loop including the contact member to successfully oppose the opposite reaction of the current flowing through the generally U-shaped current path of the switch and to provide an excess reaction which forces the stationary movable arcing members firmly together. At the same time the arrangement permits a closer spacing of the stationary switch members with the long contact supporting arms.

The angularly related portions of the current path between the movable arcing members also set up a magnetic field which is present in the arc zone between the separable arcing members and reacts strongly on the circuit interrupting arcs to blow them outwardly and into intimate contact with the cool oil in which the switch is immersed, whereby to effect the rapid extinguishment of the arcs.

The magnetic field is the resultant of several components. The magnetic field set up by the arms 76 and 62 has a horizontal axis and tends to force the arc radially outward. The field set up by the loop composed of the conducting arms of the two clamping members acts in a vertical direction. The two fields react to produce a component that acts to force the arc outward and at the same time laterally. This direction of the blow-out effect is advantageous since, because the switch components are usually contained in a cylindrical oil receptacle, the arc must travel over a longer distance before it engages the receptacle wall or the insulating liner thereof than if it were blown radially outward. The arc blow-out path is thus more or less tangential to the inner surface of the receptacle so that the arcs are deflected into large masses of oil, the dielectric strength of which is not critical to insulation of the switch, and have a long path of movement and a good chance of becoming cool and de-ionized and the gases dissipated before they come in contact with some conducting part of the switch. The direction of deflection of both arcs is in the same sense about the vertical axis of the switch so that the possibility of intermingling of the conducting gases and the resulting establishment of a single uncontrollable arc between the stationary switch member is reduced to a minimum. Each movable arcing member 86 is connected to an arm 76 only at one end, the other end being free, so that the arc can be deflected in the direction of the free end without coming in contact with a conducting part of the circuit through the arcing members.

Various changes may be made in the construction and arrangement of the parts without departing from the scope of the invention.

I claim:

1. A movable switch member for an electric switch including a vertical lifting rod,

a rigid conducting support secured to the lower end of said rod and extended on opposite sides thereof, and a generally horizontal movable contact arm having a pivotal support at one end on said conducting support at one side of said rod and having a contact member at its free end which is disposed on the opposite side of said rod, and means to connect said conducting support and contact arm electrically in series.

2. A movable switch member for an electric switch including a vertical insulating rod, a rigid conducting support carried at the lower end of said rod and extended transversely on opposite sides thereof, a horizontal arm having a pivotal support at one end thereof on said support at one side of said rod and having a contact member at its free end which is disposed on the opposite side of said rod, and means to direct current to flow in opposite directions in said arm and support.

3. A movable switch member for an electric switch including a vertical insulating rod, a rigid conducting support fixed to the lower end of said rod having a conducting section which extends transversely of said rod on opposite sides thereof, a movable contact member comprising a generally horizontal arm having a pivotal support at one end on said support which is located at one side of said rod and having a contact tip at its free end which is disposed on the opposite side of said rod, said arm and the conducting section of said support being in the same vertical plane, and means to direct current to flow through said arm and said support in a direction to bias said movable contact member in a switch closing direction by reason of the magnetic reaction of the current flowing therein.

4. A movable switch member for an electric switch including a vertical lifting rod, a contact structure carried at the lower end of said rod comprising a pair of complementary clamping members fixed to said rod, said clamping members being insulated from each other, contact members each having a pivotal connection at one end with a separate one of said clamping members, and means to direct current to flow in parallel paths through said contact members and clamping members whereby to react magnetically on said contact members to urge them in a switch closing direction.

5. A movable switch member for an electric switch including a vertical lifting rod, a transverse bridging member pivotally supported at the lower end of said rod, a rigid conducting support secured to the lower end of said rod beneath said bridging member having a horizontal conducting section which extends transversely on opposite sides of said vertical rod, a conducting arm overlying said conducting section having a pivotal connection with said support on one side of said rod

and having a contact member disposed at its free end and on the opposite side of said rod.

6. A movable switch member for an electric switch including an axial lifting rod, a transverse bridging member carried by the lower end of said rod, a rigid conducting support carried by the lower end of said rod beneath said bridging member having a horizontal conducting section which extends on opposite sides of the axis of said rod, a generally horizontal arm disposed above and parallel with said conducting section which is pivotally connected with said support at one side of said switch rod and which carries a contact member at its other and free end at the opposite side of said switch rod.

7. A movable switch member for an electric switch including a central and vertical lifting rod, a movable contact member comprising an arm which is pivotally supported at one side of said rod and extends in a generally horizontal direction across and terminates on the other side of said rod in a contact member, and a rigid conducting support for said arm which constitutes a current conducting path which is parallel with and which reacts on said arm to urge it in a switch closing direction.

8. A movable switch member for an electric switch including a vertical lifting rod, a rigid conducting support carried by the lower end of said rod having a horizontal conducting section which extends transversely on opposite sides of said rod, a movable contact arm comprising a generally horizontal arm which is disposed above and is generally parallel with said conducting section having a pivotal support at one end thereof on said support at one end of said section, and having a contact member at its free end which is disposed on the opposite side of said rod adjacent the other end of said conducting section, means normally biasing said contact member for upward movement about its pivotal support, and means electrically connecting said contact member and support arranged to direct current to flow therethrough in a direction to assist said biasing means by the magnetic forces set up by the current flowing therein.

9. A movable switch member for an electric switch including a vertical lifting rod, a rigid supporting member fixed to the lower end of said rod including a horizontal conducting section which extends transversely of said rod and on opposite sides thereof, a bridging member pivotally mounted on said support and having a central aperture through which said rod extends, an auxiliary contact member comprising a generally horizontal arm which is pivotally mounted on said support at one end and which carries a contact member at its free end, said arm having its support located at one side of said lifting rod and having its contact member

located at the opposite side thereof, said arm being above and in the same vertical plane with the conducting section of said support, resilient means normally biasing said arm in a switch closing direction, and means electrically connecting said arm with said supporting member arranged to direct current to flow in parallel paths through said clamping member and said arm whereby to exert a reactive effect on said arm substantially throughout the entire length thereof.

10. A movable switch member for an electric switch including a vertical lifting rod, a rigid conducting support carried by the lower end of said rod comprising a pair of insulated clamping members adapted to receive the end portion of said rod, said clamping members having oppositely and outwardly extended horizontal brackets which are disposed on opposite sides of said rod and which terminate in upstanding bosses, each of said clamping members and the brackets thereof constituting a horizontal current conducting path, a pair of movable contact members comprising generally horizontal arms which are pivoted at one end to the terminal bosses of said brackets and which extend on opposite sides of said rod above the horizontal current conducting paths comprising a clamping member and bracket, arcing members carried by the free ends of said arms, and electrically conducting means connecting said clamping members arranged to direct the current in said arms to flow in the horizontal path through said clamping members and brackets in a direction to urge said arms throughout the length thereof in the switch closing direction by reason of the repulsive effect of the magnetic field in the vicinity of said arms.

11. A movable switch member for an electric switch including a central and vertical lifting rod, a rigid conducting support fixed to the lower end of said rod comprising a pair of clamping members having central upstanding arms, a transverse bridging member pivotally supported on said arms and having a central aperture through which said rod extends, said clamping members having horizontally extended brackets which project on opposite sides of said rod and which terminate in upstanding bosses that are located beneath said bridging member at diagonally opposite corners thereof, said clamping members and the brackets thereof constituting horizontal current conducting paths, movable contact members comprising generally horizontal arms pivoted at one end to the bosses of said brackets and having contacts at their free ends and extended in opposite directions and on opposite sides of said switch rod in general parallel relation and in the same vertical plane with the current path through said clamping members and the brackets thereof, and means electrically connecting

the diagonally opposite ends of said clamping members which lie adjacent the pivoted ends of said arms.

12. A movable switch member for an electric switch including a central and vertical lifting rod, a rigid conducting support fixed to the lower end of said rod comprising a pair of insulated clamping members having central upstanding arms, a transverse bridging member pivotally supported on said arms and having a central aperture through which said rod extends, said clamping members having horizontally extended brackets which project on opposite sides of said rod and which terminate in upstanding bosses that are located beneath said bridging member at diagonally opposite corners thereof, said clamping members and the brackets thereof constituting horizontal current conducting paths, vertical conducting bars fixed to and upstanding above the opposite ends of said clamping members, means electrically connecting said bars whereby to connect the horizontal current paths electrically in series, and movable contact members comprising generally horizontal arms having arcing members at their free ends and having a pivotal support at their opposite ends on the respective bosses of said brackets, said arms arranged to overlie the current conducting paths including said clamping members and the brackets thereof.

13. A movable switch member for an electric switch including a central and vertical lifting rod, a rigid conducting support fixed to the lower end of said rod comprising a pair of clamping members having central upstanding arms, a transverse bridging member pivotally supported on said arms and having a central aperture through which said rod extends, said clamping members having horizontally extended brackets which project on opposite sides of said rod and which terminate in upstanding bosses that are located beneath said bridging member at diagonally opposite corners thereof, said clamping members and the brackets thereof constituting horizontal current conducting paths, movable contact members comprising generally horizontal arms pivoted at one end to the bosses of said brackets and extended in opposite directions and on opposite sides of said switch rod in general parallel relation and in the same vertical plane with the current path through said clamping members and the brackets thereof, said arms having contacts at their free ends, means electrically connecting the diagonally opposite ends of said clamping members which lie adjacent the pivoted ends of said arms, and means carried by and insulated from said clamping members having vertical attaching portions and having horizontal portions which overlie said arms whereby to support said arms against undue lateral movement due to the attractive

force of the parallel currents flowing therein and also to limit the upward movement of said arms in a switch closing direction.

14. In an electric switch the combination of a pair of spaced vertical switch members terminating in contact members at their lower ends, a movable switch member including a vertically reciprocable insulating rod which is disposed between and in the same vertical plane as said switch members, a rigid conducting support carried by the lower end of said rod having outstanding brackets which constitute with said clamping members parallel current conducting paths on opposite sides of said switch rod, bosses formed integral with the ends of said brackets, generally horizontal arms having a pivotal support at one end on said bosses and arranged to overlie the parallel current conducting paths of said support, contacts carried by the free ends of said arms, and means to direct current to flow through said arms and the current paths of said support in a direction to urge said arms throughout their length by reason of the magnetic reaction in a direction to engage said fixed contact members.

15. An electric switch comprising stationary switch members and a cooperating movable switch member having a lifting rod, a pair of current conducting contact arms located on opposite sides of said rod, each arm having a pivoted connection with said rod under a separate one of said stationary switch members and having at its free end a contact member which co-operates with said other stationary switch member, and an electric connection between said pivotally connected ends of said arms which provides conducting parts located adjacent said arms and traversed by current which reacts on said arms in a direction to urge them against said stationary switch members.

16. An electric switch comprising stationary switch members and a cooperating movable switch member having a lifting rod, a pair of current conducting contact arms located on opposite sides of said rod, each arm having a pivoted connection with said rod under a separate one of said stationary switch members and having at its free end a contact member which cooperates with said other stationary switch member, and an electric connection between said pivotally connected ends of said arms which provides conducting parts located under and parallel with said arms and traversed by current in the opposite direction to the current traversing said arms, whereby to react on said arms and to urge them for upward movement about their pivotal connections.

17. A movable switch member for an electric switch comprising stationary switch members, a movable switch member having a vertical lifting rod, a pair of parallel current carrying contact arms disposed on opposite

- sides of said rod and having pivotal connections therewith on opposite sides of said rod, contact members carried by the free ends of said arms, and an electric connection between the pivotally connected ends of said arms which provides conducting parts located in parallel proximity with said arms and traversed by current in a direction to react magnetically with the current traversing said arms and to urge said arms against said stationary switch members. 10
18. An electric switch having stationary switch members and a movable switch member including spaced pivotally supported arms having contact members at their free ends which cooperate with said stationary switch members, and a conductor electrically connecting the pivotally supported ends of said arms having sections which provide vertical loops with said arms and a horizontal loop between said arms. 15
19. An electric switch having stationary switch members and a movable switch member including spaced pivotally supported arms having contact members at their free ends which cooperate with said stationary switch members, and a conductor electrically connecting the pivotally supported ends of said arms having sections which provide vertical loops with said arms and a horizontal loop between said arms, and a lifting rod which supports said arms and conductor extended through said horizontal loop. 20
20. An electric switch having stationary switch members, a movable switch member comprising a lifting rod, a contact support on the lower end of said rod including two clamping members between which said rod is engaged, means insulating said clamping members from each other, and contact members connected each with a separate one of said clamping members. 25
21. An electric switch having stationary switch members, a movable switch member comprising a lifting rod, a contact support on the lower end of said rod including two clamping members between which said rod is engaged, means insulating said clamping members from each other, a bridging member connected with and insulated from both of said clamping members, and contact members connected each with a separate one of said clamping members. 30
22. An electric switch having stationary switch members, a movable switch member comprising a lifting rod, a contact support on the lower end of said rod including two clamping members between which said rod is engaged, means insulating said clamping members from each other, a bridging member connected with and insulated from both of said clamping members, means electrically connecting said clamping members which encircle said lifting rod, and contact members 35
- connected each with a separate one of said clamping members. 40
23. An electric switch having stationary switch members, a movable switch member comprising a lifting rod, a contact support on the lower end of said rod including two clamping members between which said rod is engaged, means insulating said clamping members from each other, and contact members each pivotally connected with a separate one of said clamping members and overlying a conducting part of the other clamping member, and means electrically connecting said clamping members. 45
24. An electric switch having stationary switch members, a movable switch member including pivotally supported parallel arms having arcing members at their free ends which cooperate with said switch members, means electrically connecting the pivoted ends of said arms so that they are traversed by current in the same direction, and insulated means which engages said arms and holds them against movement toward each other due to attractive effect of the parallel currents. 50
